UNITED STATES PATENT OFFICE.

WINFIELD E. BEVERIDGE, OF BALTIMORE, MARYLAND.

STEAM-COOKER.

SPECIFICATION forming part of Letters Patent No. 397,687, dated February 12, 1889.

Application filed May 26, 1888. Serial No. 275,151. (No model.)

To all whom it may concern:

Be it known that I, WINFIELD E. BEVERIDGE, a citizen of the United States, residing at Baltimore, in the State of Maryland, have 5 invented certain new and useful Improvements in Steam-Cookers, of which the following is a specification.

My invention relates to an improved steam-cooker for domestic use of that class which 10 comprises a boiler and several separate vessels sitting one upon the other on the boiler.

The invention is illustrated in the accompanying drawings, in which—

Figure 1 is a vertical section of the cooker. 15 Fig. 2 is a top view of the upper vessel, the cover of which is removed. Fig. 3 is a side view of one vessel. Fig. 4 is a side view in which the wall of the vessel is broken away to expose the stand-pipe to view. Figs. 5 and 20 6 are views of the false bottom used for dry-steaming.

The letter A designates the bottom vessel, which serves as a boiler. This vessel has a side lip, b, which enables the boiler to be replenished with water. The boiler furnishes steam to supply the several cooking-vessels C above it. Each cooking-vessel is entirely independent of the other, and the bottom of one sits within the top of the other. The bottom 25 30 d is flat, and may be employed alone as an ordinary stew-pan upon the stove-top. A stand-pipe, e, is attached to an opening through the bottom and slightly tapers or reduces in size toward its upper end. Each 35 stand-pipe has near its upper end an outlet or opening, f.

It will be seen by reference to Fig. 1 that when the several vessels C are in position—one upon the other—the large lower end of 40 the pipe in one vessel will receive the small upper end of the pipe in the vessel next below it. Thus the pipes e of the several vessels connect, and, together, form a continuous pipe inclosed within the vessels and leading 45 from the boiler A to the topmost vessel. By this arrangement of connected pipes each vessel will receive from the opening f a due share of steam, and the pipes are not exposed on the outside of the vessels. The upper end of 50 the pipe in the top vessel may be closed by a cap, g, and the vessel itself by a cover, G.

As shown in Fig. 4 and in the middle vessel in Fig. 1, the stand-pipe e has a band or

collar, h, loosely surrounding it. This collar has a hole, f'. The band fits about the pipe 55 where the steam-outlet f is, and may be turned thereon by grasping it with the thumb and fingers. This loose band serves to close the opening or outlet f and prevent steam from entering to the vessel, while allowing it to 60 pass up to the vessel above, or by turning the said loose band h so that the two holes f f' coincide steam may pass laterally from the pipe to the vessel. This contrivance to regulate the inflow of steam is of advantage, for 65 the reason that some articles of food—such as turnips and other green vegetables—need no water such as will come from a condensation of the steam, while other articles—such as rice, hominy, and dry fruits—are benefited by 70 such addition of water. Whether steam enters the vessel or not, each vessel will be heated sufficiently by the heat of the vessel above and below to cook well.

A false bottom, I, sits within any one or all 75 of the vessels, if desired. This false bottom has a down flange, j, at its rim, which supports it elevated, and a notch, k, to take about the stand-pipe e. This false bottom serves to keep certain articles of food above the water 80 of condensation, which may be on the bottom of the vessel. It is found that by this arrangement food may be cooked substantially alike in each and all of the vessels, and that the flavor of food in one vessel will not affect that 85 in another.

This construction, whereby the several advantages are obtained, is simpler and cheaper than others.

Having described my invention, I claim— 90

The steam-cooker herein described, consisting of a base-boiler having arranged above the same a series of receptacles provided with perforated pipes having perforated collars mounted thereon, a removable cap on the upper end of the upper tube, and a removable flanged bottom having a notch which surrounds the pipe of the receptacle, substantially as and for the purpose specified. 95

In testimony whereof I affix my signature in 100 the presence of two witnesses.

WINFIELD E. BEVERIDGE.
